United States Patent Office.

SHERMAN S. JEWETT AND FRANCIS H. ROOT, OF BUFFALO, NEW YORK.

Design No. 3,786, dated December 14, 1869.

DESIGN FOR A STOVE.

The Schedule referred to in these Letters Patent and making part of the same.

We, SHERMAN S. JEWETT and FRANCIS H. ROOT, of the city of Buffalo, in the county of Erie, and State of New York, have invented and produced a new and original Design for Stoves, of which the following is a specification.

Our invention relates to a design for the cast parts of a sheet-iron stove, consisting of a top ring or frame and cover, door, door-frame, and base-plate, all of which are constructed, in their general features, after well-known patterns, so as to form, with the requisite body of sheet-iron, a wood-stove of convenient oval or cylindrical form, but distinguished from all other stoves of this kind, by the peculiar design or ornamentation of these cast portions.

In the accompanying drawings—

Figure I is a perspective view of the top frame and cover.

Figure II is a perspective view of the door and frame and base-plate.

Like letters designate like parts in each of the figures.

A is the top ring or frame,

B, the cover,

C, the door,

D, the door-frame, and

E, the base-plate.

The ornaments of the top ring A consist of a narrow row or band, *a*, applied in relief to its convex edge, and a broader one, *a'*, arranged concentrically in its concave portion.

A very narrow row of ornaments, *b*, adorns the upwardly-projecting rim or flange, in which the cover B fits.

A basket or urn, H, formed of foliage, and provided with two scroll-shaped handles, *h*, and a pierced cover, terminating in a finial, *h'*, rises from the centre of cover B.

A wreath, *d*, of foliage, surrounds the base of said vase, and an outer ornamental band, *d'*, encloses the word "Lily," this being the name or denomination of this kind of stove.

The main portion of the cover proper is covered with convex radial flutings, *e*, enclosed in an ellipse, while outside of this ellipse, at the ends, the surface of the cover is embellished with scroll-work or arabesques, *f*.

The lily is the distinctive ornament of this stove, and a flower of this kind, with stem and leaves, is represented in relief in the centre of the moulded panel of the door C.

The four corners of the door are filled with fret-ornaments, *g*.

The convex surface of the door-frame D is ornamented in the same way as the concave portion *a'*, of the top ring A.

The edge of the base-plate E is covered with ornaments, *a'*, similar to those applied to the edge of ring A, and a concentric cord, *i*, of cable-work, is laid in the moulding formed between the edge of the base-plate and the projection to which the stove-body of sheet-iron is fitted, the convex surface of said projection being likewise embellished with ornaments, *m*.

The rounded corners of the front extension of the base-plate E are filled with scroll-work and foliage, *s*, enclosing a rosette.

We claim, as our invention—

The designs for the cast portions of a sheet-iron stove, consisting of the top ring A, cover B, provided with urn H, door C, door-frame D, and base-plate E, as shown and described.

SHERMAN S. JEWETT.
FRANCIS H. ROOT.
